F. W. PERRIN, SR.

DOOR CHECK.

1,415,225.

Specification of Letters Patent.

Patented May 9, 1922.

Application filed January 5, 1922. Serial No. 527,227.

To all whom it may concern:

Be it known that I, WILLIAM G. DISCHER, a citizen of the United States of America, and resident of Wheeling, county of Ohio, and State of West Virginia, have invented 5 certain new and useful Improvements in Door Checks, of which the following is a specification.

This invention relates to door checks, and 10 it has for its primary object to provide a check of the air-cylinder, or pneumatic, type in which a retractile closing spring is employed exterior to the cylinder and is so disposed that the piston rod which operates in 15 the cylinder is at no time subjected to bending strains.

In prior structures of the type to which the present invention relates, the closing spring has occupied a position at an angle 20 to, or out of parallel with, the cylinder and the piston rod. Obviously, such arrangement results in a lateral strain being imposed upon the piston rod, which strain becomes so considerable as the door is swung 25 to a wide open position that the rod not infrequently becomes bent, rendering the check wholly inoperative.

As hereinbefore indicated, it is the chief aim of the present invention to provide a 30 door check structure in which the position of the spring relative to the piston rod is such that bending strains imposed by the former upon the latter are eliminated.

A further object is to structurally improve 35 and simplify generally door checks of the character referred to.

In describing the invention in detail, reference is herein had to the accompanying drawings, in which—

40 Figure 1 is a front elevation of the invention applied to a door;

Figure 2 is a similar view of the invention, enlarged; and—

45 Figure 3 is an end view of the cylinder showing the hinge and hook construction.

Referring to said drawings, 1 indicates a 50 hollow cylinder, 2 a piston which is reciprocable within said cylinder, and 3 a piston rod which projects outward through the rear end of said cylinder.

Attached to the front end or head 4 of the cylinder 1, as by means of screws 5, is a plate 6 which constitutes one leaf of a hinge which has the opposite leaf 15 thereof

rigidly mounted upon a door casing 7 at a 55 suitable point over a door 8.

A bracket 9 is mounted stationarily upon the upper part of the door 8 adjacent to the hinged edge thereof, and pivotally mounted upon the upright post of said bracket is an eye-piece 10 which is carried upon the outer end of the piston rod 3. Formed integral with said eye-piece and disposed at right angles to the latter is an arm 11 designed to have attached thereto 65 one end of a retractile coil spring 12 which has its opposite end attached to one of two arms or lugs 13 and 14 carried by the cylinder-carried leaf 6 of the hinge. Said lugs, which are preferably formed integral with 70 said hinge-leaf 6, are disposed vertically, one thereof extending upward and the other extending downward such distance that when the spring 12 is attached thereto the latter will not engage the cylinder. 75

The eye-piece 10 is reversible so that the arm 11 thereof may be disposed either in upright position, as shown in Fig. 1, or in depending position, as shown in Fig. 2, thus making provision for mounting the spring 80 in a position either overlying or underlying the cylinder, as may be preferred or as may be deemed expedient.

The lugs 13 and 14 and the arm 11 have such relative lengths that the spring interposed between them lies directly parallel to the cylinder and, consequently, exerts force in a direction parallel to said cylinder where- 85 by the door is actuated to close, following opening, without any such lateral strain being imposed upon the piston rod as would tend in any way to either bend said rod or produce binding of the latter upon the cyl- 90 inder. 95

What is claimed is—

1. A door check comprising a cylinder, a piston reciprocable within said cylinder, a rod attached to said piston and movable through the rear end of said cylinder, a bracket carried by the door, an eye-piece 100 carried by said piston rod and having a vertical arm, said eye-piece being reversible for mounting upon said bracket with the arm thereof occupying either upstanding or depending position, a hinge carried by the 105 front end of said cylinder and attached to the door casing, oppositely disposed lugs carried on said front end of the cylinder, and a re-

tractile coil spring disposed parallel to said cylinder and connecting the arm of the eye-piece to one or the other of said lugs according as said arm occupies an upstanding or depending position.

2. A door check comprising a cylinder, a piston reciprocable within said cylinder, a rod attached to said piston and movable through the rear end of said cylinder, a bracket carried by the door, an eye-piece carried by said piston rod and having a vertical arm, said eye-piece being reversible for mounting upon said bracket with the arm thereof occupying either upstanding or depending position, a hinge of leaf type having one leaf thereof rigidly mounted on the front end of the cylinder at right angles to the axis of the latter and the opposite leaf mounted upon the door casing over the door, lugs formed on that leaf of the hinge which is carried by the cylinder, said lugs being oppositely disposed and projecting above and below the level of said cylinder, and a retractile coil spring disposed parallel to said cylinder either above or below the latter, according as the arm of said eye-piece is disposed in upstanding or depending position, said spring connecting said arm to the upper or lower of said lugs, according as it occupies an upper or lower position.
- 10 15 20 25

3. A door check comprising a cylinder, a piston reciprocable within said cylinder, a rod attached to said piston and movable

through the rear end of said cylinder, a bracket carried by the door, an eye-piece carried by said piston rod and having a vertical arm, said eye-piece being reversible for mounting upon said bracket with the arm thereof occupying either upstanding or depending position, a hinge of leaf type having one leaf thereof rigidly mounted on the front end of the cylinder at right angles to the axis of the latter and the opposite leaf mounted upon the door casing over the door, lugs formed on that leaf of the hinge which is carried by the cylinder, said lugs being oppositely disposed and projecting above and below the level of said cylinder, and a retractile coil spring disposed parallel to said cylinder either above or below the latter, according as the arm of said eye-piece is disposed in upstanding or depending position, said spring connecting said arm to the upper or lower of said lugs, according as it occupies an upper or lower position.
